CLAIM

The ornamental design for a container with surface indicia, as shown and described.

DESCRIPTION

FIG. 1 is a front perspective view of a container with surface indicia, embodying our new design;
 FIG. 2 is a front view of the container with surface indicia of FIG. 1;
 FIG. 3 is a first side view of the container with surface indicia of FIG. 1;
 FIG. 4 is a back view of the container with surface indicia of FIG. 1;
 FIG. 5 is a second side view of the container with surface indicia of FIG. 1;
 FIG. 6 is a top view of the container with surface indicia of FIG. 1; and
 FIG. 7 is a bottom view of the container with surface indicia of FIG. 1;
 FIG. 8 is a front perspective view of a container with surface indicia, embodying an embodiment of our new design;
 FIG. 9 is a front view of the container with surface indicia of FIG. 8;
 FIG. 10 is a first side view of the container with surface indicia of FIG. 8;

FIG. 11 is a back view of the container with surface indicia of FIG. 8;
 FIG. 12 is a second side view of the container with surface indicia of FIG. 8;
 FIG. 13 is a top view of the container with surface indicia of FIG. 8; and
 FIG. 14 is a bottom view of the container with surface indicia of FIG. 8;
 FIG. 15 is a front perspective view of a container with surface indicia, embodying an embodiment of our new design;
 FIG. 16 is a front view of the container with surface indicia of FIG. 15;
 FIG. 17 is a first side view of the container with surface indicia of FIG. 15;
 FIG. 18 is a back view of the container with surface indicia of FIG. 15;
 FIG. 19 is a second side view of the container with surface indicia of FIG. 15;
 FIG. 20 is a top view of the container with surface indicia of FIG. 15; and
 FIG. 21 is a bottom view of the container with surface indicia of FIG. 15;
 FIG. 22 is a front perspective view of a container with surface indicia, embodying an embodiment of our new design;
 FIG. 23 is a front view of the container with surface indicia of FIG. 22;
 FIG. 24 is a first side view of the container with surface indicia of FIG. 22;
 FIG. 25 is a back view of the container with surface indicia of FIG. 22;
 FIG. 26 is a second side view of the container with surface indicia of FIG. 22;
 FIG. 27 is a top view of the container with surface indicia of FIG. 22; and
 FIG. 28 is a bottom view of the container with surface indicia of FIG. 22;
 FIG. 29 is a front perspective view of a container with surface indicia, embodying an embodiment of our new design;
 FIG. 30 is a front view of the container with surface indicia of FIG. 29;
 FIG. 31 is a first side view of the container with surface indicia of FIG. 29;
 FIG. 32 is a back view of the container with surface indicia of FIG. 29;
 FIG. 33 is a second side view of the container with surface indicia of FIG. 29;
 FIG. 34 is a top view of the container with surface indicia of FIG. 29; and
 FIG. 35 is a bottom view of the container with surface indicia of FIG. 29;
 FIG. 36 is a front perspective view of a container with surface indicia, embodying an embodiment of our new design;
 FIG. 37 is a front view of the container with surface indicia of FIG. 36;
 FIG. 38 is a first side view of the container with surface indicia of FIG. 36;
 FIG. 39 is a back view of the container with surface indicia of FIG. 36;
 FIG. 40 is a second side view of the container with surface indicia of FIG. 36;

FIG. 41 is a top view of the container with surface indicia of FIG. 36; and,

FIG. 42 is a bottom view of the container with surface indicia of FIG. 36.

The broken lines shown illustrate portions of the container with surface indicia and form no part of the claimed design.
